UNITED STATES PATENT OFFICE

154,905

DESIGN FOR A HEAT LAMP

Conkling Chedister, Livingston, N. J., assignor to
 Infra-Appliances Corporation, New York, N. Y.,
 a corporation of New York

Application April 27, 1949, Serial No. 2,301

Term of patent 7 years

(Cl. D48—20)

To all whom it may concern:

Be it known that I, Conkling Chedister, a citizen of the United States of America, and resident of Livingston, county of Essex, State of New Jersey, have invented a new, original, and ornamental design for a Heat Lamp, of which the following is a specification, reference being had to the accompanying drawings, forming part thereof.

Figure 1 is a front perspective view of a heat lamp, showing my new design;

Figure 2 is a rear perspective view of the heat lamp shown in Fig. 1, the upper portion in a substantially vertical position.

Figure 3 is a top plan view of the lamp shown in Figure 2;

Figure 4 is a side elevation of the lamp shown in Figure 2; and

Figure 5 is a rear elevation of the lamp shown in Figure 2.

I claim:

The ornamental design for a heat lamp, as shown.

CONKLING CHEDISTER.
